UNITED STATES PATENT OFFICE.

JOHN ALLEN HEANY, OF JERSEY CITY, NEW JERSEY, ASSIGNOR TO LINDSAY AUTO PARTS COMPANY, OF INDIANAPOLIS, INDIANA, A CORPORATION OF INDIANA.

IGNITION DEVICE FOR MOTOR-VEHICLES.

1,301,053.

Specification of Letters Patent. Patented Apr. 15, 1919.

Original application filed July 27, 1910, Serial No. 574,030. Divided and this application filed November 21, 1917. Serial No. 203,171.

To all whom it may concern:

Be it known that I, JOHN ALLEN HEANY, a citizen of the United States, residing at Jersey City, in the county of Hudson, and 5 State of New Jersey, have invented certain new and useful Improvements in Ignition Devices for Motor-Vehicles, of which I declare the following to be a full, clear, and exact description.

10 This invention relates particularly to that type of dynamo electric machines, which have gas engine ignition mechanism incorporated in their structure. This application is a division of my co-pending application, 15 Serial No. 574,030, filed July 27, 1910.

The object of the invention is to embody in a single unit, a dynamo electric machine, a distributor, and a timer for internal combustion engines. Another object is to 20 dispose the ignition elements in the dynamo, so that they will be easily accessible and detachable, and have a direct positive driving relationship with the dynamo armature shaft. Another object is to provide means for automatically preventing an excessive flow of 25 current in the ignition circuit should the engine stop. Further objects, and objects relating to economies of manufacture and details of construction, will definitely appear from the detailed description to follow.

I accomplish the objects of my invention by the devices described in the following specification; my invention is clearly defined and pointed out in the appended claims.

30 A structure constituting a preferred embodiment of my invention is illustrated in the accompanying drawings, forming a part of this specification, in which—

Figure I is a view showing the dynamo in 40 place on an automobile chassis;

Fig. II is a diagrammatical view illustrating the electrical devices connected in proper circuit;

Fig. III is a view of the dynamo with the 45 ignition devices shown in section;

Fig. IV is a sectional end view of the machine taken substantially on the line IV—IV of Fig. III;

Fig. V is a detail sectional view of the 50 automatic switch controlling device.

Similar reference characters refer to similar parts throughout the several views, and the sectional views are taken looking in the

direction of the little arrows at the ends of the section lines.

55 In the accompanying drawings, the dynamo electric machine 1, is illustrated as connected by gears 2, 3, 4, to the shaft 2, of the engine 6. This engine is for convenience illustrated as of the four-cylinder type having its cylinders 7, 8, 9, 10, arranged to receive a supply of explosive mixture through the manifold 11^a, and carbureter 12^a, from a main supply tank 13^a, with intermediate connection 14^a. The chassis frame is indicated at 15^a, and bears the various parts of the mechanism making up an ordinary chassis frame, the several parts of which need no detail description.

60 In the diagrammatic view illustrated in Fig. II, the engine cylinders 7, 8, 9, 10, are illustrated as provided with spark plugs 11 to 14, inclusive, which plugs, of course, have one of their terminals grounded in the engine and frame while the other is connected 65 with the respective circuit wires 15 to 18, inclusive. These line-wires terminate in the relatively stationary contacts of the distributor, D, the movable contact 19, thereof being connected with a circuit wire 20, which, 70 through the secondary coil b', and primary coil b, of the spark coil B, is connected with the make and break device E, through its stationary contact e. The movable contact 21, actuated by a cam or suitable device 22, 75 is connected through a line wire 23, with the switch contact 24. The opposite side of the circuit 26, which runs from the primary coil b, is connected with a switch contact 27.

75 There are also two switch contacts 28, 29, which respectively connect with the circuit line wires 30, 31, that connect with the dynamo electric machine A.

This dynamo electric machine A, is, of course, provided with an armature, a, and 95 with a series field winding C, and a shunt field winding F, which, through the circuit 30, 31, connect the dynamo-electric machine with a storage battery K, through the switch L, which, as indicated herein, is formed as 100 a unit with the switch member l, that controls the lines 23, 26, of the ignition circuit that is also connected with the storage battery K and the main line wires of the dynamo electric machine when the switch L, l, 105 is closed.

A lamp circuit 32, 33, is indicated as controlled by a switch M, which switch is connected with the line circuit 30^a, 31^a.

Of course, it is understood that the various controlling switches of the main line circuit may be varied to suit any particular condition. It is preferred, however, that the switches L, l, are so arranged and interlocked that the main line circuit 30, 31, of 10 the generator will be closed in relation to the storage battery K, and main line 30^a, 31^a, only when the ignition circuit 23, 26, is closed, the ignition circuit and main line circuit being opened and closed simultaneously; 15 otherwise, it is apparent that with the engine at rest, the storage battery K, might discharge through the dynamo electric machine, and the ignition circuit also, provided the switch O was closed.

20 As illustrating the dynamo electric machine more in detail, reference is made to Figs. III, IV and V, wherein the armature shaft 50, is illustrated as suitably mounted upon anti-friction bearings 51, and attached 25 to a gear 52, which gear is in mesh with a gear 53, mounted upon anti-friction bearings 54, and providing a means for rotating a make and break cam 55.

The armature 56, is provided with suitable 30 commutator and brush connections arranged in the head-piece 57. These parts are not shown in detail nor are the fields arranged within the casing 58, specifically shown in detail.

35 To the front of the main casing of the dynamo electric machine is secured a casing 59, which provides a suitable bearing for the support of the gear 52, and an axially movable sleeve 60. This sleeve, as illustrated 40 herein, is, through a spline 61, connected with a sectional shaft 62, which, in turn, is connected through the gears 2, 3, 4, with the main shaft of the engine.

The gear 52, has an extended sleeve 63, 45 provided with helical slots or cam grooves 64, within which are arranged pins 65, that are secured to the axially movable sleeve 60. The sleeve 60, is also provided with a grooved actuator 66, which, through any suitable 50 lever 67, may be utilized to actuate a switch device such as illustrated in diagram at L, l, or for any purpose for controlling the various circuits.

In Figs. III and IV, I have illustrated the 55 particular form of timing mechanism employed.

The gear 53, heretofore referred to and the timing cam 55, are mounted to rotate upon the anti-friction bearings 54, which are supported upon a spindle 68, which spindle is secured in the face plate 69, of the machine in any desired manner.

An insulating plate 70, provided with suitable conductors 71, to 74, inclusive, provides 65 a means for bringing the inner terminals of

said conductors successively into position to take current from the plate 75 on the rotating member 53. The opposite side of the circuit is connected through a conductor 76, to a ring plate 76' and thence through the 70 conductor 77, to the plate 75.

Secured to an insulating plate, 78, is a stud 79, upon which is mounted a trip finger 80, held in normal position by a spring 81, and having a lip 82, and a lever arm 83. The latter comes in contact and is moved by the bosses 84, of the timing cam 55, so that the vibrator spring 85, will be drawn away from the contact post 86, at given periods to break the circuit. The vibrator spring 85, is mounted 80 in a block 87, in any suitable manner.

With this arrangement of parts, it is apparent that the timing device will always operate synchronously with the generating apparatus and both devices are conveniently 85 coalesced to form a unit which, with the ordinary controlling devices, may be mounted upon the engine in lieu of an ordinary magneto.

In diagram in Fig. II, there is illustrated a 90 switch O, which may be utilized for making and breaking the ignition circuit. This, of course, is such a switch as is ordinarily employed on automobiles and must be closed in order to effectively operate the other elements. On the other hand, to stop the engine, this ignition switch may be opened and thereupon the engine, through its reduced speed, will permit battery K to drive the 95 dynamo electric machine A as a motor and cause the automatic switch lever 67, to be moved through the sleeve 60, to properly cut out the ignition and generator circuits at switches L, l, as hereinbefore described. It is also to be noted, should the engine stop 100 for any reason while the switch O is still closed, or should the switch O be closed accidentally while the engine is at rest, that the excessive current which would ordinarily 105 flow through the ignition circuit under such conditions, will be entirely prevented by the action of the switch l which always automatically opens when the engine speed falls below a certain value.

Obviously, the elements might be arranged 110 in various forms of juxtaposition or the details of the mechanism might be varied without departing from the spirit or intent of the invention, as defined in the claims appended herewith.

What I claim as my invention and desire 115 to secure by Letters Patent, is:—

1. In an ignition system for internal combustion engines, the combination with a spark producing device including a winding, 120 of a source of electrical energy comprising a storage battery and dynamo adapted to charge the same through an automatically controlled circuit, an ignition circuit adapted to connect said source of energy with said 125 130

- winding, a switch for interrupting the flow of current in said ignition circuit independently of current flow in the other circuits of the system, a circuit interrupting member 5 periodically actuated by the engine for controlling and timing the current flow in said ignition circuit, and means intercalated in said ignition circuit for automatically preventing excessive current flow therein when 10 the rate of periodic actuation of said circuit interrupting member falls below a certain value.
2. In an ignition system for internal combustion engines, the combination with a current transforming device comprising high and low tension windings, of a source of electrical energy comprising a storage battery and charging means therefor connected thereto through an automatically controlled 15 circuit, a primary circuit adapted to connect said source of energy with said low tension winding, a switch for interrupting the flow of current in said primary circuit independently of current flow in the other circuits 20 of the system, a circuit interrupting member periodically actuated by the engine for controlling and timing the current flow in said primary circuit, and current actuated means intercalated in said primary circuit for automatically preventing excessive current flow 25 therein when the rate of periodic actuation of said circuit interrupting member falls below a certain value.
3. In an ignition system for variable speed 30 internal combustion engines, the combination with a spark producing device including a winding, of a source of electrical energy comprising a storage battery and charging means therefor connected thereto through an automatically controlled circuit, an ignition circuit adapted to connect said source of energy with said winding, a normally closed circuit interrupting member periodically actuated by the variable speed engine 35 for controlling and timing the current flow in said ignition circuit, and current actuated means intercalated in said primary circuit for automatically preventing excessive current flow therein when the rate of periodic actuation of said circuit interrupting member falls below a certain value.
4. In an ignition system for internal combustion engines, the combination with a 40 spark producing device including a winding, of a source of electrical energy comprising a storage battery and charging means therefor connected thereto through an automatically controlled circuit, an ignition circuit adapted to connect said source of energy with said winding, a normally closed circuit interrupting member periodically actuated by the variable speed engine 45 for controlling and timing the current flow in said ignition circuit, and current actuated means intercalated in said ignition circuit for automatically preventing excessive current flow therein when the rate of periodic actuation of said circuit interrupting member falls below a certain value.
5. In an ignition system for variable speed 50 internal combustion engines, the combination with a spark producing device including a winding, of a source of electrical energy comprising a storage battery and charging means therefor connected thereto through a manually closed circuit, an ignition circuit adapted to connect said source of energy with said winding, a normally closed circuit interrupting member periodically actuated by the variable speed engine 55 for controlling and timing the current flow in said ignition circuit, and current actuated means intercalated in said primary circuit for automatically preventing excessive current flow therein when the rate of periodic actuation of said circuit interrupting member falls below a certain value.
6. In an ignition system for internal combustion engines, the combination with a spark producing device including an ignition circuit, of a source of electrical energy comprising a storage battery and a dynamo arranged to charge the same, single manually operable means for simultaneously connecting said battery to said ignition circuit and said dynamo, a circuit interrupting 60 member periodically actuated by the engine for controlling and timing the current flow in said ignition circuit, and current actuated means intercalated in said ignition circuit for automatically preventing excessive current flow therein when the rate of periodic actuation of said circuit interrupting member falls below a certain value.
7. In an ignition system for internal combustion engines, the combination with a 65 spark producing device including a winding, of a source of electrical energy comprising a storage battery and charging means therefor connected thereto through an automatically controlled circuit, an ignition circuit adapted to connect said source of energy with said winding, a circuit interrupting member periodically actuated by the engine for controlling and timing the current flow in said ignition circuit, and electro-mechanical means intercalated in said primary circuit for automatically preventing excessive 70 current flow therein when the rate of periodic actuation of said circuit interrupting member falls below a certain value.
8. In an ignition system for internal combustion engines, the combination with a spark producing device including an ignition circuit, of a source of electrical energy comprising a storage battery and a dynamo arranged to charge the same, single manually operable means for simultaneously connecting said battery to said ignition circuit and said dynamo, a circuit interrupting member periodically actuated by the engine for controlling and timing the current flow in said ignition circuit, and current actuated means intercalated in said ignition circuit for automatically preventing excessive current flow therein when the rate of periodic actuation of said circuit interrupting member falls below a certain value.
9. In an ignition system for internal combustion engines, the combination with a 75 spark producing device including a winding, of a source of electrical energy comprising a storage battery and charging means therefor connected thereto through a manually closed circuit, an ignition circuit adapted to connect said source of energy with said winding, a normally closed circuit interrupting member periodically actuated by the variable speed engine 80 for controlling and timing the current flow in said ignition circuit, and current actuated means intercalated in said primary circuit for automatically preventing excessive current flow therein when the rate of periodic actuation of said circuit interrupting member falls below a certain value.
10. In an ignition system for internal combustion engines, the combination with a spark producing device including an ignition circuit, of a source of electrical energy comprising a storage battery and a dynamo arranged to charge the same, single manually operable means for simultaneously connecting said battery to said ignition circuit and said dynamo, a circuit interrupting member periodically actuated by the engine for controlling and timing the current flow in said ignition circuit, and current actuated means intercalated in said ignition circuit for automatically preventing excessive current flow therein when the rate of periodic actuation of said circuit interrupting member falls below a certain value.

In testimony whereof I affix my signature.

JOHN ALLEN HEANY.
